(57) CLAIM

I claim the ornamental design for a golf tee, as shown and described.

DESCRIPTION

FIG. 1 is a perspective view of the golf tee showing my new design;

FIG. 2 is a front view thereof; the right and left side views, as well as the rear view being identical;

FIG. 3 is a bottom view thereof; and,

FIG. 4 is a top view thereof.

1 Claim, 1 Drawing Sheet
